(57) **CLAIM**

The ornamental design for a sensor carrier, as shown and described.

DESCRIPTION

FIG. 1 is an isometric view of a sensor carrier having sensors disposed therein;

FIG. 2 is a front view of the sensor carrier of FIG. 1;

FIG. 3 is a back view of the sensor carrier of FIG. 1;

FIG. 4 is a left view of the sensor carrier of FIG. 1;

FIG. 5 is a right view of the sensor carrier of FIG. 1;

FIG. 6 is a top view of the sensor carrier of FIG. 1; and,

FIG. 7 is a bottom view of the sensor carrier of FIG. 1.

Where applicable, elements are shown in broken lines herein for illustrative purposes only, and form no part of the claimed design.

1 Claim, 7 Drawing SheetsFIG. 1

FIG. 2

FIG. 3

FIG. 4

FIG. 5

FIG. 6

FIG. 7
